FOREIGN PATENT DOCUMENTS

WO WO 93/14688 8/1993

Primary Examiner — Karen E Eldridge Powers

(74) Attorney, Agent, or Firm — Alston & Bird LLP

CLAIM

The ornamental design for a gas water bottle adaptor, as shown and described.

DESCRIPTION

FIG. 1 is a perspective view of a gas water bottle adaptor according to our new design;

FIG. 2 is another perspective view thereof;

FIG. 3 is a front plan view thereof;

FIG. 4 is a rear plan view thereof;

FIG. 5 is a top plan view thereof; and,

FIG. 6 is a bottom plan view thereof.
